UNITED STATES PATENT OFFICE.

JOHN M. BEACH AND GEORGE FLETCHER, OF GRAND RAPIDS, MICHIGAN, ASSIGNORS
TO STROMBERG-CARLSON TELEPHONE MANUFACTURING COMPANY, OF ROCHE-
STER, NEW YORK, A CORPORATION OF NEW YORK.

DESIGN FOR A RADIOCABINET OR SIMILAR ARTICLE.

Application filed March 30, 1927. Serial No. 21,397. Term of patent 7 years.

To all whom it may concern:

Be it known that we, JOHN M. BEACH and GEORGE FLETCHER, citizens of the United States, residing at Grand Rapids, county of Kent, State of Michigan, have invented a new, original, and ornamental Design for Radio Cabinet or Similar Article, of which the following is the specification, reference being had to the accompanying drawing, forming a part thereof.

Figure 1 is a perspective view of a radio cabinet showing our new design and Figure 2 is a fragmentary detail view of one of the supports shown to a somewhat enlarged scale.

We claim:

The ornamental design for a radiocabinet or similar article as shown.

JOHN M. BEACH.
GEORGE FLETCHER.
